(57) **CLAIM**

The ornamental design for a jewelry element, as shown and described.

DESCRIPTION

FIG. 1 is a front perspective of a jewelry element in a first embodiment;

FIG. 2 is a front elevation of the jewelry element of FIG. 1; FIG. 3 is a rear elevation of the jewelry element of FIG. 1; FIG. 4 is a right side view of the jewelry element of FIG. 1; FIG. 5 is a left side view of the jewelry element of FIG. 1; FIG. 6 is a top view of the jewelry element of FIG. 1; FIG. 7 is a bottom view of the jewelry element of FIG. 1; FIG. 8 is a rear perspective view of the jewelry element of FIG. 1; and

FIG. 9 is another rear perspective view of the jewelry element of FIG. 1;

FIG. 10 is a front perspective of a jewelry element in a second embodiment;

FIG. 11 is a front elevation of the jewelry element of FIG. 10;

FIG. 12 is a rear elevation of the jewelry element of FIG. 10; FIG. 13 is a right side view of the jewelry element of FIG. 10;

FIG. 14 is a left side view of the jewelry element of FIG. 10; FIG. 15 is a top view of the jewelry element of FIG. 10; FIG. 16 is a bottom view of the jewelry element of FIG. 10; FIG. 17 is a rear perspective view of the jewelry element of FIG. 10; and,

FIG. 18 is another rear perspective view of the jewelry element of FIG. 10.

The broken lines in the drawings illustrate portions of the jewelry element and form no part of the claimed design.

1 Claim, 14 Drawing Sheets
